US00D957766S

(12) **United States Design Patent** (10) **Patent No.:** **US D957,766 S**
(45) **Date of Patent:** **** Jul. 12, 2022**

(54) **FABRIC CARE APPLIANCE**

(71) Applicant: **WHIRLPOOL CORPORATION**,
Benton Harbor, MI (US)

(72) Inventors: **Kevin B. Ayers**, St. Joseph, MI (US);
Andrew C. Kubasiak, St. Joseph, MI (US); **Anna C. Schelling**, Stevensville, MI (US); **Mark W. Schulz**, Benton Harbor, MI (US)

(73) Assignee: **Whirlpool Corporation**, Benton Harbor, MI (US)

(**) Term: **15 Years**

(21) Appl. No.: **29/812,812**

(22) Filed: **Oct. 25, 2021**

Related U.S. Application Data

(62) Division of application No. 29/764,487, filed on Dec. 30, 2020, now Pat. No. Des. 938,110, which is a division of application No. 29/682,855, filed on Mar. 8, 2019, now Pat. No. Des. 909,694.

(57) **CLAIM**

The ornamental design for a fabric care appliance, as shown and described.

DESCRIPTION

FIG. 1 is a front perspective view of a fabric care appliance according to the design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The portions of the article shown in broken line form no part of the claimed design.

1 Claim, 7 Drawing Sheets
